TREATMENT OF TEXTILES WITH ACETYLENE DIUREA DERIVATIVES

Dmitry M. Gagarine and Henry Repokis, Danville, Va., assignors to Dan River Mills, Incorporated, a corporation of Virginia

No Drawing. Application February 29, 1952, Serial No. 274,310

10

10 Claims. (Cl. 117—139.4)

The present invention relates to the treatment of cellulosic fabrics with aqueous solutions of heat hardening resin forming materials and acid liberating catalysts to provide improved crease angle recovery, dimensional stability and other desirable properties with a minimized concomitant decrease in wear life of the treated fabric. More particularly the invention relates to improving the effectiveness or efficiency of acetylene diurea methylols and methylol ethers by proper neutralization of fabrics and the use of catalysts, hereinafter referred to as quaternary ammonium catalyst having the general formula:

wherein R is an aliphatic radical having from 14 to 22 carbon atoms, P is a pyridinium or lower aliphatic substituted pyridinium group, X is the anion of a strong acid and A is a connecting linkage selected from the group consisting of an amide, an ester, and an ether.

Treatment of fabrics with compounds falling in the class of acetylene diurea methylols and methylol ethers is shown in German Patent No. 702,146. However, commercially feasible methods heretofore used in applying these compounds have not produced results substantially better than those obtained with other and more universally used resin forming materials such as urea formaldehyde and melamine formaldehyde.

The normal steps of treating textile fabrics with resin forming materials to produce crease-angle recovery are:

1. Application of an aqueous solution of resin and catalyst to the fabric.
2. Drying of the fabric at a relatively high speed at the lowest temperature which will not cure the resin, and
3. Curing the resin forming material on the thus dried impregnated fabric.

Production of fabrics having a high degree of crease-angle recovery has been limited in the past to fabrics having sufficient initial strength to permit a considerable reduction in tear strength of the treated fabrics without bringing the tear strength to the danger point. In other words, all prior processes capable of producing satisfactory crease-angle recovery also produced a concomitant decrease in tear strength and, accordingly, it has been generally necessary to choose a fabric which will be strong enough for normal wear even after a major reduction in tear strength.

The tear strength of fabrics treated in accordance with the present invention is reduced much less, thus permitting the selection of sheer fabrics having a low initial tear strength before treatment to produce crease-angle recovery.

According to the present invention the general steps of treating the fabrics are the same as those outlined above. It has now been found that the beneficial results of a

2

minimum reduction in tear strength for any given degree of crease angle recovery can be obtained by the combination:

5. Neutralizing the fabric being treated at some stage prior to the final setting of the resin.
2. Utilizing an acetylene diurea derivative as a resin forming material, and
3. Using one of the above defined quaternary ammonium catalysts.

The neutralization of the fabric can be accomplished in any one of several ways, the critical factor being the requirement that substantially all sodium ions on the fabric be neutralized. A satisfactory neutralization test is to titrate the amount of sodium ions on the fabric as sodium hydroxide. When the thus tested sodium hydroxide is less than .01%, the fabric is sufficiently neutral. One method of neutralizing the fabric consists in washing the fabric in a mild acid solution and rinsing the acid treated fabric with water having a pH of less than 7.

Another method of neutralizing the fabric is the use of a low molecular weight acid releasing material in the fabric treating bath which is capable of easily penetrating cellulosic fibers and which releases acid during the heating of the fabric to neutralize sodium ions in situ. It is important that the amount of acid releasing material used for neutralization be less than that causing catalytic action inasmuch as premature catalysis will produce low tear strengths which are avoided by proper use of the present invention. It has now been found that about 1.1 to 1.5 mols of acid releasing material will neutralize 1 mol of alkali to produce optimum results of neutralization without catalysis. Suitable acid releasing materials for sodium ion neutralization are 2,2 methyl amino propanol hydrochloride, monoethanol amine hydrochloride, diethanol amine hydrochloride, monoammonium phosphate, diammonium phosphate, triammonium phosphate, ammonium chloride, and a sulfur dioxide-formaldehyde complex.

It has now been found that quaternary ammonium catalysts having the formula:

wherein R is an aliphatic radical having from 14 to 22 carbon atoms; P is a pyridinium or lower aliphatic substituted pyridinium group, X is the anion of a strong acid and A is a connecting linkage selected from the group consisting of an amide, an ester, and an ether, will release acid only in the curing step and that these catalysts produce particularly beneficial results with the hereinafter defined acetylene diurea derivatives. These catalysts are known to be generally equivalent to other acid catalysts for other resin forming materials, such as urea formaldehyde and melamine formaldehyde, but the unexpected result obtained by using these catalysts with acetylene diurea derivatives does not extend to use of these catalysts with other resin forming materials such as urea formaldehyde and melamine formaldehyde.

The gist of the present invention is the discovery that the above defined quaternary ammonium catalysts have a marked superiority over conventional catalysts when used to catalyze the reaction of acetylene diurea derivatives with neutralized cellulose, which marked superiority is not present with other resin forming materials normally used in the treatment of textile fabrics for the production of crease-angle recovery.

Catalytic compounds which have been tested and

proven to be generally satisfactory for purposes of this invention are:

Stearamido methyl pyridinium chloride.
Stearamido methyl pyridinium nitrate.
Stearamido methyl beta picolinium chloride.
Stearamido methyl beta picolinium nitrate.
Octadecyl oxymethyl pyridinium chloride.
Octadecyl oxymethyl pyridinium nitrate.
Octadecyl oxymethyl pyridinium beta picolinium chloride.
Octadecyl oxymethyl pyridinium beta picolinium nitrate.
Octadecyl oxymethyl 2 ethyl 5 methyl pyridinium chloride.
Stearoyl oxymethyl pyridinium chloride.
Palmitamido methyl pyridinium chloride.
Hexadecyl oxymethyl pyridinium chloride.
Stearamido methyl gamma picolinium chloride.
Stearamido methyl gamma picolinium nitrate.
Stearamido methyl beta gamma picolinium chloride.
Stearamido methyl beta gamma picolinium nitrate.

A preferred catalyst falling into the generic grouping heretofore referred to as quaternary ammonium catalysts is of undetermined composition. It is believed to contain stearamido methyl pyridinium nitrate as one component and it is known that methylol groups are present in some component of the composition. The preferred catalyst, hereinafter referred to as a stearamido methyl pyridinium nitrate composition, is prepared as follows:

EXAMPLE A

Preparation of stearamido methyl pyridinium nitrate composition

413 lbs. of stearamide (Armid HT sold by Armour & Co.) and 103 lbs. paraformaldehyde are added with stirring to 196 lbs. of perchloroethylene (a substantially inert solvent for purposes of this invention) held at 160° F. The paraformaldehyde and stearamide are reacted at 210° F. for one hour after which 133 lbs. of pyridine nitrate are added. The reaction continues at 210° F. for 30 minutes. The mixture is stirred throughout the reaction.

The pyridine nitrate used in this reaction is an approximately 88% pure product containing excess pyridine to the extent that a 10% solution of it has a pH of about 4.35. It has been found that if 55 lbs. of fuming, HNO_3 are slowly added to 77 lbs. of pyridine with cooling and stirring, a satisfactory pyridine nitrate can be produced.

The reaction product of paraformaldehyde, stearamide, and pyridinium nitrate is artificially slowly cooled and solvents are added to form the finished product as follows:

When the reaction mass reached 198° F.—add 77 lbs. butanol
When the reaction mass reaches 176° F.—add 33 lbs. isopropanol
When the reaction mass reaches 150° F.—add 56 lbs. methanol.

The product is light tan paste at room temperature and tends to stiffen to a solid at lower temperature. It is water dispersable in warm water for immediate use as a catalyst.

The term acetylene diurea derivatives as used in this specification includes those methylols and methylol ethers of acetylene diurea which are water soluble and reactive with cellulose. Typical compounds which have been tested and found generally satisfactory are:

Dimethylol acetylene diurea.
Tetramethylol acetylene diurea dimethylol.
The acid condensation product of trimethylol, acetylene diurea with itself.
The trimethyl ether of trimethylol acetylene diurea.
The tri-isopropyl ether of trimethylol acetylene diurea.

The methylol acetylene diurea resinous products may be prepared in two steps, the first of which comprises

producing the acetylene diurea by reacting glyoxal with urea in an acid medium, and then producing the methylol thereof by reacting the acetylene diurea with formaldehyde in a basic medium and finally condensing or polymerizing the reaction product in an acid medium. Along with the trimethylol acetylene diurea, some dimethylol acetylene diurea may be formed without disadvantage.

The formaldehyde which is reacted with acetylene diurea may be in the form of Formalin or as paraformaldehyde.

Illustrative but non-limiting examples of the preparation of some preferred acetylene diurea derivatives on a pilot plant scale is as follows:

EXAMPLE B

Preparation of acetylene diurea

Glyoxal (30.3% solution) ..... 1680 lbs.—1 mol.
Urea ..... 1800 lbs.—3.4 mols.
20 Hydrochloric acid solution (28% HCl by weight) ..... 150 lbs.

Place the glyoxal in a stainless steel reaction kettle equipped with stirrer, steam coils, cooling jacket and a thermometer. Add the urea while stirring constantly. 25 Much of the urea remains undissolved; but sufficient does dissolve to cause the temperature to fall as low as 40° F. Now add the hydrochloric acid, which brings the pH to between 1 and 2. Start heating the mixture by means of the steam coil. As the mixture heats, an exothermic reaction starts. At about 150° F. a granular white precipitate forms. When the temperature reaches 190° F. the reaction is well under way, and the heating is discontinued. If left alone at this stage, the reaction mixture continues to heat up and finally boils and foams 30 violently. Accordingly, the temperature is allowed to rise to 200° F. and then the mixture is cooled by means of the cooling jacket to 195° F. It is kept at this temperature of 195–200° F. for ten minutes, at which time the intensity of the reaction has abated. The temperature is then allowed to rise to 200–205° F. and kept at this range for another thirty minutes. At the end of that time the exothermic reaction is over, as shown by the fact that the mixture starts to cool normally.

The mixture is then cooled to about 180° F. merely 45 to facilitate handling, and brought to a pH of 7–8 with about 20 lbs. of sodium hydroxide dissolved in water. The pH before the addition of the NaOH has risen from the initial 1 to 2 to between 4 and 5.

At this stage the reaction mixture is a yellow brown 50 slurry, which, if not stirred constantly and vigorously, separates rapidly into a cream-colored solid, the acetylene diurea, and a coffee-colored liquid. If properly stirred, it is sufficiently homogenous so that samples may be withdrawn for analysis.

55 This neutral slurry is then pumped into a large, 2500-gallon tank, equipped with a perforated false bottom fitted with a filter cloth. The tank resembles a very large Buckner type funnel, and like the funnel the space under the perforated false bottom is connected to a vacuum 60 pump so that the liquid above the false bottom can be filtered through the filter cloth.

Such a reaction as above described gives approximately 900 lbs. dry weight of acetylene diurea, corresponding to a yield of approximately 72%. Five such reactions 65 are usually run to give a total of 4500 lbs. dry weight of acetylene diurea. The acetylene diurea is stirred with about five times its weight of water, and the water filtered off. This stirring and filtering is continued until a sample of the acetylene diurea gives a resinous product 70 of the desired lightness of color. After the final washing and the removal of as much water as possible by filtration, the cake contains approximately 4500 lbs. dry weight of acetylene diurea, corresponding to an over-all yield of approximately 72%, and approximately 6000 75 lbs. of retained water.

EXAMPLE C

Preparation of the trimethylol acetylene diurea resinous product

To the wet cake above described is added 7700 lbs. of Formalin, which contains 37.5% formaldehyde by weight. This is in the ratio of three mols of formaldehyde to one mol of acetylene diurea. The mixture is then stirred until it is a thick slurry and NaOH solution added slowly and carefully until the pH is between 9 and 10. The amount of NaOH required depends upon the amount of formic acid which is always present in commercial Formalin in small but variable amounts.

A mild exothermic reaction takes place, and the acetylene diurea dissolves to give a light yellow-brown solution of fairly low viscosity. The mixture is stirred until it is certain that all of the acetylene diurea has dissolved. It is then brought to a pH of 4 or slightly lower, by careful addition of HCl, and allowed to stand at least twelve hours. Some polymerization takes place, and the viscosity increases until the solution is about as viscous as thin motor oil.

At the end of this time the mixture is brought to a pH of 6 to 7 with NaOH, which stops the polymerization. The solution is filtered and is ready for use.

For preparing the above acid condensation resinous product, it is desirable to use three mols of formaldehyde to each mol of acetylene diurea, but this ratio may be varied within the range of two to four mols of the former to form the dimethylol and tetramethylol acetylene diureas.

EXAMPLE D

Preparation of the methyl ethers of trimethylol acetylene diurea

To 1 mol of trimethylol acetylene diurea, add 218 mls. or 5.5 mols of methanol. A clear solution results. 7.0 ml. of concentrated sulfuric acid is then added with stirring. In about two hours the etherification is complete, as is shown by complete solubility of the condensation product in methyl alcohol and its partial solubility in acetone.

The products prepared in the above examples and other materials within the scope of this invention may be used for treating textiles in accordance with the following typical but non-limiting examples:

EXAMPLE 1

An aqueous solution was prepared containing the following ingredients:

10% of the product produced according to Example C (50% solids).
2% 2, 2, methylamino propanol hydrochloride, 50% solids.
1% of a stearamido methyl pyridinium nitrate composition prepared as described in Example A.
2% corn starch (50% fluidity).
.3% non-ionic wetting agent.
.1% anti-foam.

A pad box was filled with this solution and a carded cotton gingham fabric running 5.2 yards per pound was padded in a conventional manner with the pad roll pressure adjusted to permit a pickup of about 80% padding liquid based on the weight of the fabric. The thus padded fabric was run directly into a tenter frame drying device heated to about 120° C. at a speed sufficient to remove the water without curing the resin. The thus treated fabric was passed through a curing oven at 180° C. for 70 seconds, at which time the resin was cured.

The anti-foam and the wetting agent are not necessary for all running conditions but were added in the above example to improve commercial operating conditions. The corn starch was added to body the fabric and give a slightly crisper hand, but can be omitted if a softer

hand is desired. In place of the starch a thermo plastic resinous material such as polyvinyl acetate may be used. The 2, 2 methylamino propanol hydrochloride was added in an amount calculated to counteract the effect of residual alkali on the fabric.

EXAMPLE 2

A combed gingham running 4.5 yards per pound was treated in the same manner as the carded gingham in Example 1 with the formula as follows:

10 8% of the products of the product produced according to Example C.
15 2% 2, 2, methylamino propanol hydrochloride—(50% solids).
20 2.4% a stearamido methyl pyridinium nitrate composition prepared according to Example A.
25 87.6% water.

The gingham produced in accordance with this example was characterized by a beautiful hand characteristic of finest combed goods. The fabric had a very high crease resistance and only a slight degradation of tear strength.

EXAMPLE 3

25 The carded gingham fabric of Example 1 was soured with a 0.25% sulphuric acid and rinsed in a non-alkaline water bath to be freed of all residual alkali not exceeding .01% measured as NaOH.

The thus soured fabric was treated in the manner set forth in Example 1 with the pad box solution as follows:

30 20% of the product made according to Example C.
.75% a stearamido methyl pyridinium nitrate composition prepared according to Example A.
35 79.25% water.

The thus treated fabric showed a crease resistance similar to that of the fabric treated in Example 1 with little difference in the over-all strength properties. The increased amount of resin appears to have made little difference in any of the qualities of the fabric from the fabric of Example 1.

EXAMPLE 4

45 A neutralized carded gingham fabric was treated in the manner set forth in Example 1 except that the aqueous pad box solution contained the following:

50 10% of the product produced according to Example C. (50% solids.)
2% 2,2,methylamino propanol hydrochloride. 50% solids.
55 1% octadecyl oxymethyl pyridinium chloride.

The fabric treated in accordance with this example had generally the same properties as the fabric treated in Example 1.

EXAMPLE 5

60 A neutralized carded gingham fabric was treated in the manner set forth in Example 1 except that the aqueous pad box solution contained the following:

65 10% of the product produced according to Example C. (50% solids.)
2% 2,2,methylamino propanol hydrochloride. 50% solids.
1% octadecyl ester of methyl pyridinium chloride.

The fabric treated in accordance with this example had generally the same properties as the fabric treated in Example 1.

EXAMPLE 6

70 A neutralized combed gingham fabric was treated in the manner set forth in Example 1 except that the aqueous pad box solution contained the following:

75 10% of the product produced according to Example C. (50% solids.)

2%, 2,2-methylamino propanol hydrochloride. 50% solids.
1% stearamido methyl pyridinium chloride (a 60% solids product sold by Du Pont as Zefan AP).

The fabric treated in accordance with this example had generally the same properties as the fabric treated in accordance with Example 2.

EXAMPLE 7

A neutralized combed gingham fabric was treated in the manner set forth in Example 1 except that the aqueous pad box solution contained the following:

10% of the product produced according to Example C. (50% solids.)
2% 2,2-methylamino propanol hydrochloride. 50% solids.
1% stearamido methyl pyridinium sulfate.

The fabric treated in accordance with this example had generally the same properties as the fabric treated in accordance with Example 2.

EXAMPLE 8

A neutralized combed gingham fabric was treated in the manner set forth in Example 1, except that the aqueous pad box solution contained the following:

10% of the product produced according to Example C. (50% solids.)
2% 2,2-methylamino propanol hydrochloride. 50% solids.
1% stearamido methyl beta picolinium nitrate.

The fabric treated in accordance with this example showed the smallest reduction in tear strength per unit of crease-angle recovery improvement of any of the fabrics treated in accordance with the present invention.

EXAMPLE 9

A combed gingham fabric was treated in the manner set forth in Example 1 except that the aqueous pad box solution contained the following:

10% of the product produced according to Example C. (50% solids.)
2% 2,2-methylamino propanol hydrochloride. 50% solids.
1% stearamido methyl gamma picolinium nitrate.

The fabric treated in accordance with this example had generally the same properties as the fabric treated in accordance with Example 2.

EXAMPLE 10

A neutralized combed gingham fabric was treated in the manner set forth in Example 1 except that the aqueous pad box solution contained the following:

10% of the product produced according to Example C. (50% solids.)
2% 2,2-methylamino propanol hydrochloride. 50% solids.
1% stearamido methylol beta gamma picolinium nitrate.

The fabric treated in accordance with this example had generally the same properties as the fabric treated in accordance with Example 2.

EXAMPLE 11

An aqueous solution was prepared containing the following ingredients:

7% tetramethylol acetylene diurea (50% solids).
2% 2,2-methylamino propanol hydrochloride (50% solids).
1% of a stearamido pyridinium nitrate composition prepared as described in Example A.
.3% non-ionic wetting agent.
.1% anti-foam.

A pad box was filled with this solution and a combed cotton gingham fabric running 4.5 yards per pound was padded in a conventional manner with the pad roll pressure adjusted to permit a pickup of about 80% of the padding liquid based on the weight of the fabric. The thus padded fabric was run directly into a tenter frame drying device heated to about 120° C. at a speed sufficient to remove the water without curing the resin. The thus treated fabric was passed through a curing oven at 180° C. for 70 seconds, at which time the resin was cured.

EXAMPLE 12

An aqueous solution was prepared containing the following ingredients:

15 12% dimethylol acetylene diurea.
2% ammonium chloride.
1% stearamido methyl beta picolinium nitrate.
.3% non-ionic wetting agent.
.1% anti-foam.

A pad box was filled with this solution and a combed cotton gingham fabric running 4.5 yards per pound was padded in a conventional manner with the pad roll pressure adjusted to permit a pickup of about 80% of the padding liquid based on the weight of the fabric. The thus padded fabric was run directly into a tenter frame drying device heated to about 120° C. at a speed sufficient to remove the water without curing the resin. The thus treated fabric was passed through a curing oven at 180° C. for 70 seconds, at which time the resin was cured.

The fabric treated in accordance with this example had generally the same properties as the fabric treated in accordance with Example 2.

EXAMPLE 13

An aqueous solution was prepared containing the following ingredients:

10% of the trimethyl ether of trimethylol acetylene diurea.
2% diammonium phosphate.
1% stearamido methyl beta picolinium nitrate.
.3% non-ionic wetting agent.
.1% anti-foam.

A pad box was filled with this solution and a combed cotton gingham fabric running 4.5 yards per pound was padded in a conventional manner with the pad roll pressure adjusted to permit a pickup of about 80% of the padding liquid based on the weight of the fabric. The thus padded fabric was run directly into a tenter frame drying device heated to about 120° C. at a speed sufficient to remove the water without curing the resin. The thus treated fabric was passed through a curing oven at 180° C. for 70 seconds, at which time the resin was cured.

The fabric treated in accordance with this example had generally the same properties as the fabric treated in accordance with Example 2.

EXAMPLE 14

An aqueous solution was prepared containing the following ingredients:

11% of the tri-isopropyl ether of trimethylol acetylene diurea.
65 2% diethanol amine.
1% stearamido methyl pyridinium nitrate.
.3% non-ionic wetting agent.
.1% anti-foam.

A pad box was filled with this solution and a combed cotton gingham fabric running 4.5 yards per pound was padded in a conventional manner with the pad roll pressure adjusted to permit a pickup of about 80% of the padding liquid based on the weight of the fabric. The thus padded fabric was run directly into a tenter frame

drying device heated to about 120° C. at a speed sufficient to remove the water without curing the resin. The thus treated fabric was passed through a curing oven at 180° C. for 70 seconds, at which time the resin was cured.

The fabric treated in accordance with this example had generally the same properties as the fabric treated in accordance with Example 2.

The "hand" of the fabrics treated in accordance with this invention may be varied by addition of standard fabric finishing agents to the pad box solutions. In general, it has been found that the softening action of the quaternary ammonium catalysts, as defined above, is sufficient for producing a soft "hand." Harsher effects can be obtained with such additives as starch, polyvinyl acetate, etc.

Permissible modifications and changes in the above-described processes of the present invention are indicated in the appended claims.

We claim:

1. The process of treating cellulosic textile fabric to improve its crease angle recovery with a minimum reduction in tear strength per unit of crease angle improvement, which comprises impregnating said fabric with an aqueous solution of a resin forming methylol acetylene diurea and a quaternary ammonium catalyst having the formula

wherein R1 is the residue of a higher fatty acid having from 14 to 22 carbon atoms, X is the anion of a strong acid, R2 and R3 are hydrogen or a lower alkyl group and A is a connecting linkage selected from the group consisting of an amide, an ester and an ether, the catalyst being capable of releasing acid only at temperatures in excess of about 130° C., acidifying the fabric to neutralize substantially all residual alkali, drying the fabric at a temperature below 130° C. and heating the fabric to a temperature substantially in excess of 130° C. to cure the resin forming methylol acetylene diurea, said neutralization being effected at some time prior to the final curing of the resin forming methylol acetylene diurea.

2. The process of treating cellulosic textile fabric to improve its crease angle recovery with a minimum reduction in tear strength per unit of crease angle recovery improvement, which comprises impregnating said fabric with a water solution of a methylol acetylene diurea and a quaternary ammonium catalyst having the formula:

wherein R1 is the residue of a higher fatty acid having from 14 to 22 carbon atoms, X is the anion of a strong acid, R2 and R3 are hydrogen or a lower alkyl group and A is a connecting linkage selected from the group consisting of an amide, an ester and an ether, drying the thus impregnated fabric and heating the thus dried fabric to cure the methylol acetylene diurea.

3. The process of treating cellulosic textile fabric to improve its crease angle recovery with a minimum reduction in tear strength per unit of crease angle recovery improvement, which comprises impregnating said fabric

5 with a water solution of a methylol acetylene diurea and a quaternary ammonium catalyst having the formula

10 15 wherein R1 is the residue of a higher fatty acid having from 14 to 22 carbon atoms, X is the anion of a strong acid, R2 and R3 are hydrogen or a lower alkyl group and A is a connecting linkage selected from the group consisting of an amide, an ester and an ether, drying the thus impregnated fabric and heating the thus dried fabric to a temperature substantially in excess of 130° C. to cure the methylol acetylene diurea.

4. The process of treating cellulosic textile fabric to improve its crease angle recovery with a minimum reduction in tear strength per unit of crease angle recovery improvement, which comprises impregnating said fabric with a water solution of a methylol acetylene diurea and a stearamido methyl pyridinium nitrate composition containing stearamido methyl pyridinium nitrate with methylol groups, drying the thus impregnated fabric and heating the thus dried fabric to cure the methylol acetylene diurea.

5. The process of treating cellulosic textile fabric to improve its crease angle recovery with a minimum reduction in tear strength per unit of crease angle recovery improvement, which comprises impregnating said fabric with a water solution of a methylol acetylene diurea and stearamido methyl beta picolinium nitrate, drying the thus impregnated fabric and heating the thus dried fabric to cure the methylol acetylene diurea.

wherein R_1 is the residue of a higher fatty acid having from 14 to 22 carbon atoms, X is the anion of a strong acid, R_2 and R_3 are hydrogen or a lower alkyl group and A is a connecting linkage selected from the group consisting of an amide, an ester and an ether, drying the thus impregnated fabric at a temperature which will not decompose said quaternary ammonium catalyst, heating the thus dried fabric at a temperature which will decompose said quaternary ammonium catalyst to release acid for catalyzing the final setting of said acetylene diurea derivative, and neutralizing the fabric at some time prior to the final curing of the methylol acetylene diurea.

8. The process of treating cellulosic textile fabric to improve its crease angle recovery with a minimum reduction in tear strength per unit of crease angle recovery improvement, which comprises impregnating said fabric with a water solution of a methylol acetylene diurea and a quaternary ammonium catalyst having the formula

wherein R_1 is the residue of a higher fatty acid having from 14 to 22 carbon atoms, X is the anion of a strong acid, R_2 and R_3 are hydrogen or a lower alkyl group and A is a connecting linkage selected from the group consisting of an amide, an ester and an ether, acidifying the fabric to neutralize it, drying the thus impregnated fabric at one temperature, and heating the thus dried fabric at a substantially higher temperature which will decompose said quaternary ammonium catalyst and thereby release acid for catalyzing the final setting of said acetylene diurea derivative, said neutralization being effected at some time prior to the final curing of the methylol acetylene diurea.

9. The process of treating cellulosic textile fabric to improve its crease angle recovery with a minimum reduction in tear strength per unit of crease angle recovery improvement, which comprises impregnating said fabric with a water solution of a methylol acetylene diurea, 2,2-methyl amino propanol hydrochloride and a quaternary ammonium catalyst having the formula

wherein R_1 is the residue of a higher fatty acid having from 14 to 22 carbon atoms, X is the anion of a strong acid, R_2 and R_3 are hydrogen or a lower alkyl group and A is a connecting linkage selected from the group consisting of an amide, an ester and an ether, said 2,2-methyl amino propanol hydrochloride being present in the amount required to neutralize the fabric to remove all residual alkali substantially in excess of 0.01% measured as sodium hydroxide, drying the thus impregnated fabric at a temperature which will not decompose said quaternary ammonium catalyst, heating the thus dried fabric at a temperature which will decompose said quaternary ammonium catalyst and thereby releasing acid for catalyzing the final setting of said methylol acetylene diurea, said neutralization being effected at some time prior to the final curing of the methylol acetylene diurea.

10. The process of treating cellulosic textile fabric to improve its crease angle recovery with a minimum reduction in tear strength per unit of crease angle recovery improvement, which comprises the step-wise procedure of first neutralizing the fabric with an acid wash, then impregnating said fabric with a water solution of a methylol acetylene diurea and a quaternary ammonium catalyst having the formula:

wherein R_1 is the residue of a higher fatty acid having from 14 to 22 carbon atoms, X is the anion of a strong acid, R_2 and R_3 are hydrogen or a lower alkyl group and A is a connecting linkage selected from the group consisting of an amide, an ester and an ether, drying the thus impregnated fabric and finally heating the thus dried fabric to cure the methylol acetylene diurea.
